(57) **CLAIM**

The ornamental design for a stylus holder, as shown and described.

DESCRIPTION

FIG. 1 is a front isometric view of a stylus holder showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is bottom view thereof;

FIG. 8 is a front isometric view of a stylus holder of FIGS. 1-7 showing features disclaimed;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front isometric view of a stylus holder of FIGS. 8-14 with the broken line features omitted for clarity;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The broken line showing of various features of the stylus holder in FIGS. 8-14 are for environmental purposes only and form no part of the claimed design.
